UNITED STATES PATENT OFFICE.

HERMAN A. SPERLICH, OF HIGHLAND PARK, MICHIGAN, ASSIGNOR TO CRYSTAL WASHING MACHINE COMPANY, OF DETROIT, MICHIGAN, A CORPORATION OF MICHIGAN.

WRINGER SUPPORT.

1,420,157.

Specification of Letters Patent. Patented June 20, 1922.

Application filed March 21, 1918, Serial No. 223,732. Renewed May 3, 1921. Serial No. 466,529.

To all whom it may concern:

Be it known that I, HERMAN A. SPERLICH, a citizen of the United States, and residing at Highland Park, in the county of Wayne 5 and State of Michigan, have invented a new and Improved Wringer Support, of which the following is a specification.

The invention relates to wringers for washing machines and is an improvement 10 on that shown and claimed in my application for United States Letters Patent Serial Number 158607, filed March 30, 1917. More particularly, the invention consists in an arm or bracket so constructed as to conform to 15 the side of one upright of the frame and to extend out underneath said arm and its companion member to form a firm support. The invention further consists in an arm 20 of the nature referred to having an upstanding longitudinal rib that both greatly stiffens the construction and is received in slots in the lower ends of the uprights of the frame for the purpose of properly retaining the frame in position and in alignment with 25 its constituent parts. The invention further consists in the details of construction shown, described and claimed.

In the drawings, Fig. 1 is a perspective view showing a preferred embodiment of 30 the invention. Fig. 2 is a fragmentary vertical section through the driving mechanism. Figs. 3, 4 and 5 are respectively a plan view, a side elevation and an end view of the swingable arm on which the frame of the 35 wringer is carried.

The wringer itself may be of any preferred construction and preferably comprises the wooden uprights 1 which are joined at the top in any suitable way and which have 40 upper slots 2 for the shafts 3 and 4 of the wringer rollers 5 and 6, the latter being held in proper relation to the former by springs 8. The uprights are also joined at a lower level by clothes guiding bars 9 45 and have in their lower ends aligned slots 10 (Fig. 2) and 11 (Fig. 1).

Extending across the lower end of the wringer from side to side is a bar 12 of a swingable arm, said bar having an upstanding central longitudinal flange 13 that is received in the slots 10 and 11 and is connected to corresponding uprights by bolts 14 and 15. At its inner end, the bar merges in a vertical flange 16 which extends up 55 along the side of the corresponding upright

and is connected thereto by bolts 18. The arm also includes a web 19 that lies on the side of the flange 16 opposite from the wringer and terminates at top and bottom, respectively, in the downwardly opening 60 cup-shaped head 20 (perforated centrally at 21, Fig. 3) and the perforated brace 22, the latter including the tapering reinforcing flanges 23. The arm is also preferably widened and cored out at 24 to provide clearance for the end of the shaft 3, the inner end of which has a cross pin 25 received in a slot in a bevel gear 26 that turns in the head 20.

The arm has cooperating therewith a support including an upwardly opening centrally perforated cup-shaped head 28 upon the upper surface of which the lower annular face of the head 20 bears, together with an overhanging perforated arm 29 and a connecting portion 30. A pivot bolt 31 75 passes through the perforations in the elements 29—20—28—22 and, with the bearing surfaces of the cup-shaped heads, forms a strong substantial support for the arm. The latter may be swung about said bolt and held 80 in any one of three positions by means of a spring-pressed latch 32 pivoted at 33 in a slot 34 in the portion 30. Mounted in the portion 30 is a bevel gear 36 which is driven by an inclined shaft 38 and meshes with a 85 double bevel gear 39 that, in turn, drives the gear 26.

In the embodiment shown, the tiltable drain board 40 is detachably and resiliently held against the lower side of the clothes 90 guiding bar 9 by a pair of arched compression springs 41 which are attached to the lower side of the board and bear on the upper face of the flange 13. The drain board may, however, be held in position by other 95 means.

It is evident that the details of the parts, particularly the elements of the pivot and the driving gears, may be changed within wide limits. I do not, therefore, wish to be 100 limited except as indicated by the subjoined claims.

I claim:—

1. In a wringer support, a one-piece wringer supporting arm including an upstanding flange adapted to fit one side of a side upright of a wringer, said arm also including a head and a brace below the head, the head and brace having aligned perforations, a web uniting the head and brace to 110

the flange and having reinforcing flanges substantially along its lower edge approximately in line with the base of the flange.

2. In combination, a wringer support having a supporting arm with an upstanding flange adapted to engage a wringer frame, a second upstanding flange adapted to engage said wringer frame, a web integral with said second flange divided at its outer edge forming spaced portions one of said portions being provided with a head, a supporting member disposed between said spaced portions pivotally carrying said support and cooperating with said head to provide a housing for wringer operating elements.

3. In a wringer support, a one piece wringer supporting member adapted to fit against the wringer and embodying a head and a brace below the head having aligned vertical perforations, the supporting member also having a horizontal perforation to receive a driving shaft for the wringer, a pivot pin in said vertical perforations, and a relatively movable supporting member having a cylindrical extension mounted on the pivot pin between the head and brace and co-operating with the head to provide a housing for the driving mechanism for the wringer.

HERMAN A. SPERLICH.
